(57) CLAIM

I claim the ornamental design for a delicate undergarment laundering cage, as shown.

DESCRIPTION

FIG. 1 of the drawings is a perspective view showing the front, top, and right side of a delicate undergarment laundering cage embodying the design of my invention; FIG. 2 is a top plan view;

FIG. 3 is a front elevation view;

FIG. 4 is a side elevation view of the right side;

FIG. 5 is a bottom plan view;

FIG. 6 is a side elevation view of the left side;

FIG. 7 is a back elevation view; and,

FIG. 8 is a perspective view similar to FIG. 1 with a lid portion in an open position.
